FERTILIZER SPREADER

Michael V. Bazilli, Oakville, Ontario, and Stanley G. Siddall, Orangeville, Ontario, Canada, assignors to Lilliston Implement Company, Albany, Ga., a corporation of Georgia

Filed Sept. 3, 1965, Ser. No. 86,856

Term of patent 14 years

(Cl. D35—2)

FIG.1

FIG.2

FIG.3

FIG.4

FIG. 1 is a side elevational view of a fertilizer spreader embodying our new design;

FIG. 2 is an end elevational view of the fertilizer spreader shown in FIG. 1;

FIG. 3 is a top plan view of the fertilizer spreader shown in FIG. 1; and

FIG. 4 is a front elevational view of the fertilizer spreader shown in FIG. 1.

The dominant features of my design reside in the portions shown in full lines.

We claim:

The ornamental design for a fertilizer spreader, substantially as shown and described.
